VARIABLE INDUCTANCE FREQUENCY MODULATION PHONOGRAPH SYSTEM

Robert Boudreaux, Delcambre, La.

Application December 11, 1944, Serial No. 567,685

6 Claims. (Cl. 179—100.4)

1

This invention relates to the reproduction of phonographic records by means of electrical oscillations and it has for its primary object to use frequency modulated high frequency oscillations for this purpose.

It is a well known fact that reproduction of phonographic records by means of electrical oscillations, although in many respects a vast improvement over the direct reproduction of the record, nevertheless does not eliminate the "background" of noises completely, this being due mainly to the rhythmical character of the disturbances, most of which are connected with the sweeping of the phonographic stylus or needle over the record surface. Disturbances of this character cause an irregular periodical or rhythmical movement of the stylus or needle which are, therefore, able to influence or "modulate" the oscillation which is produced by means of the record. These disturbances, distortions and additions on account of their character, which is intimately associated with the principle on which a reproducing arrangement is based, cannot be eliminated completely.

Part of the background of disturbing noise accompanying a reproduction is moreover produced, due to causes which need not be explained here, during the making of the record by means of a cutter and the usual type of reproduction arrangement whose performance is geared to the highest degree of absolute fidelity of reproduction which is obtainable has clearly no means for eliminating disturbances of this kind.

Discrimination between disturbances without tone quality (called hereinafter "noise") and musical or other well-defined tones is impossible in the usual reproduction system in which the stylus is caused to oscillate in accordance with the sinuosities of the sound track. All hitherto known filter arrangements interposed between the stylus and the reproduction arrangement are unsuitable for this purpose as their activities are restricted to certain frequency bands. Systems, which distinguish between tone of musical quality to a certain extent and noises lacking this quality, do, however, exist and these are the frequency and phase modulation systems employed in radio transmission.

This modulation system permits a discrimination between sounds of tone quality and other sounds which are termed noise; the sounds of tone quality of a given amplitude permit a shifting of the carrier wave over a frequency range which is different from the range obtained by sounds without this quality and thus the ratio

2

in the received signal intensity between sounds of tone quality and sounds without such quality ("noise") is much improved after the process of frequency modulation.

5 It will be seen from the above that this improvement of the ratio between reproduction and noise intensity which furnishes a much improved quality of the former is not dependent on anything but the quality (including amplitude) of 10 the generated sounds and it is, therefore, immaterial whether these sounds of undesirable quality which ought to be eliminated originated during the recording or during the reproduction process.

15 The invention, therefore, relates to sound reproducing arrangements, in which sound reproduction by means of a stylus from a record is performed by means of frequency modulated waves. The invention consists in an improved arrangement 20 for producing frequency modulation in an oscillation circuit operated by an oscillation furnishing the carrier wave directly by means of the stylus moving over a record.

One of the objects of the invention is to provide 25 an arrangement of this type which is carried by the tone arm and is contained within said arm. While the "receiver" forming that part of the arrangement in which the frequency modulated wave is subject to demodulation, amplification, etc., may be located anywhere and preferably even at a distance, the frequency modulator should be closely associated with the tone arm and form as compact and as small a unit as possible. This is not only necessary in order to 30 produce a commercially sound arrangement, with a small and compact portable apparatus similar to the mechanical talking machines, but is also necessary on account of the short waves used which can be shielded effectively against disturbances merely if all connections are short and if 35 all unwanted capacities, etc., are eliminated.

A further object of the invention consists in providing 40 an arrangement in which the stylus may directly influence the frequency of a circuit connected with the oscillator producing the carrier wave.

A number of still further objects and advantages gained by the instant system is described 45 more fully in the following specification illustrating one modification of the invention. It is, however, to be understood that the fact that merely one modification of the system is illustrated is not to be interpreted in a limitative sense. Indeed, the invention relates to a new 50 system of reproduction of phonographic records

and the way in which the system may be embodied in actual phonographic apparatus is not limited to the single embodiment shown. To experts skilled in this art and in the art of radio transmission, it will be clear that, while using the presently described principles as a base, other embodiments may suggest themselves or may be developed without in the least departing from the essence or spirit of the invention described.

The invention is illustrated in the accompanying drawings in which

Figure 1 is an elevational view partly in section of the tone arm of a phonographic reproduction apparatus (talking machine) showing the general arrangement of the parts.

Figure 2 is a plan or top view of the tone arm showing its curvature.

Figure 3 is a perspective view of the stylus and of the members and parts associated with it.

Figure 3a is an elevational cross sectional view, of the arrangement shown in Figure 3, the cross section being taken along the medium plane.

Figure 4 is a diagram of the connections of the parts or members forming the frequency modulation and the arrangement producing the frequency modulated wave.

Figure 5 is a diagram of the connections of a "receiver" or sound producing arrangement of the apparatus which is supposed to be arranged at a distance from the record containing part of the reproducing arrangement.

The sound reproduction method used according to the present invention consists in producing a carrier wave which is frequency modulated by the variation in electrical oscillations carried by the stylus of a phonographic arrangement. The arrangement, when compared with the frequency modulation systems used in radio transmissions, is much simplified and reduced to the minimum of components; this simplification is rendered possible by the fact that frequency modulation is used here only for filtering purposes, and that, therefore, a great number of requirements supposed to be indispensable in radio transmission may be neglected. It may also be mentioned in this connection, that although short waves are used and are even indispensable, the arrangement is by no means confined to the narrow frequency band of ultra-short waves used for high frequency modulated radio transmission. Short waves of all kinds may be used, the selection depending mainly on the possibility to obtain the most compact and most simple arrangement which is not open to interference from outside.

The entire frequency modulation arrangement (which in the present arrangement includes the oscillator and all members and parts whose function it is to cooperate in the production of a frequency modulated wave) is arranged within a tone arm 1, which is shaped approximately in the way in which the customary tone arms are shaped. It is slightly curved at one end 2 (Figure 2) which is hollow and accommodates the frequency modulator. At the other end a counter-balancing weight 3 is arranged, which is intended to balance the increased weight of the end 2 due to the inclusion of the modulator.

The tone arm 1 is carried by a tone arm support 4 which is pivoted to it by means of pivot bolts 5, which are journaled in rubber bearings 6. The support preferably rests on a ball bearing, designated in general by the reference numeral 7. The support rests on the ball 8 of the bearing which is supported by a post 9 projecting from a base plate 10. The latter is firmly se-

cured by means of a screw 11 in the customary box 12 carrying the arrangement.

The post is provided with indentations or cuts or with a groove 13 into which small set screws 14, attached to the support, enter. They prevent the support 4 and the tone arm 1 from being lifted or accidentally displaced.

The rear or stylus carrying part 2 of the tone arm usually termed "cradle" is provided with a slanting or slightly inclined bottom part 15, through which the needle 16 projects. This gives the needle a slight inclination which is supposed to be of a certain advantage when the stylus travels over the record.

15 The stylus 20 carrying the needle 16 may be of any approved type and it is here shown as consisting of a flattened cylindrical slotted member provided with the customary projections or shoulders 19. It may be fixed or supported according to any customary or approved method.

16 In order to mount the entire arrangement in the cradle, it is preferable, according to the invention, to use two L-shaped holding pieces 17, 17a, arranged transversely in the cradle between 25 which the stylus 20 may be held. For this purpose, the frontal faces of the legs of the L-shaped holders are provided with cylindrical or half-moon shaped recesses 23 of semi-circular cross sections accommodating the shoulders 19 of the 30 stylus 20 over which rubber sleeves 18 have been slid.

35 It is to be understood that the way in which the stylus is attached is essential. Any well known stylus support may be used, its function being merely to hold the stylus in such a way that the oscillations of the needle are transmitted to the upper part of the stylus with the greatest fidelity and without introducing any distortion.

40 To the upper part of the stylus 20 a plunger or core 21 is fixed projecting into the interior of a coil 22. This plunger or core is fixed to the stylus by any known means, cementing or gluing being in this case preferable. The plunger or core 21 is a so-called dust core made of powdered steel or 45 in order to provide extreme lightness of aluminum.

46 Behind the piston or core 21 a rubber damper 24 is arranged, a paper disc 25 being interposed 50 between it and the core. The disc is made of very thin paper and its function is merely to prevent the rubber from sticking to the metal which frequently takes place during periods of rest when direct contact is made. The rubber damper 24 is 55 mounted on a coil support 26, which is provided to hold the coil in its place. The coil support 26 itself is held by means of a projection or stem 27 which is secured in one of the L-shaped holders.

56 The coil 22 consists of a coil form 28 upon which the coil windings of coil 22 are wound. Around 60 said coil a second coil form 30 with a coil 31 of a few windings only is arranged whose function will be explained later in connection with the diagram of connections.

65 On the other side of the stylus 20, another rubber damper 32 is arranged whose end face is covered with a paper disc 33. It serves to damp the free oscillations of the stylus 20.

66 As will be clear from the above description, the 70 oscillations imparted to the needle and transmitted to the stylus will cause the latter to perform transversal oscillations which impart axial or longitudinal oscillations to the plunger or core within the coil. Thereby the inductance of the 75 coil is varied in accordance with these oscillations.

tions. These variations of inductance are utilized in a way to be described.

As the stylus is rubber cushioned on both sides its free oscillations will be damped very effectively.

In order to be able to regulate the damping action the damping rubber pad 32 is mounted on a rod 34 whose position may be adjusted by means of a screw 35, which is held in the L-shaped support 17a facing the support 17. Preferably the screw is buried within the hole 36 which is provided with the screw threads and after adjustment of the screw has been made during assembly or after testing the arrangement, the remainder of the hole 36 is filled with paraffin, or some other substance, in order to prevent adjustments by the user of the apparatus which would upset the correct damping.

The hollow end 2 of the tone arm 1 moreover contains all the components of the oscillatory circuit, viz: an oscillator tube 37 mounted on a socket 37a on which two or even three condensers (not shown in Figure 1) may be mounted. It moreover contains an adjustable condenser 38 (Figure 1), one plate of which is provided with a pressure knob 39, projecting outwardly. By means of the knob 39 the capacity of the condenser may be adjusted, and this permits to adjust the frequency of the oscillations generated in the oscillator.

The coil of the oscillation circuit is the coil 22 whose location and mounting on the core in the cradle has already been described. As will be seen from the diagram shown in Figure 4, the oscillator tube 37 forms part of the usual oscillation generator arrangement in whose grid and plate circuit the coil 22, the condenser 38 and the two condensers 39 and 40 are arranged. When the inductance of coil 22 varies by means of the core 21 penetrating into its interior to a varying extent, the inherent frequency of the circuit varies and the frequency of the oscillation which is then generated varies in proportion to the amplitude of the sound oscillations produced in the sound record. By means of the coil 31, whose influence on the frequency is negligible and which surrounds coil 22, the frequency modulated oscillations generated in the oscillator tube are transmitted to an aerial or directly to a "receiver."

An antenna may be used for various purposes. First, it is sometimes desirable to operate the sound producing speaker and the pick-up at different places. Then, it is frequently desirable to keep the persons listening to the sound production away from a generator which is operated on the short wave band, as in spite of shielding, undesirable disturbances may be introduced by persons on account of their capacity with respect to ground. Finally, direct connections in this case are only preferable when certain precautionary measures are taken which are unnecessary in the event of transmission through the air.

If an aerial is used, a condenser 41, shortening the effective length of the antenna, is preferably inserted.

The "receiving" arrangement containing the speaker which may be used in the event of a transmission through the air is shown in Figure 5, the arrangement being clearly about the same if direct transmission takes place, the coupling of the receiving circuit 42 with the aerial is then merely replaced by a coupling with the circuit containing the modulated oscillations. The cir-

cuit connections shown in Figure 5 are purely conventional and need not be explained in detail as the diagram merely shows the customary type of receiver for frequency modulation. A heterodyne receiver generating an intermediate frequency may be employed, if desired. As will be clear to the expert skilled in this art, the oscillations are demodulated, detected in the detector 43 and after having been amplified are sent to the speaker 44.

From the above it will be seen that the construction of a phonographic apparatus in the form of a gramophone, or the like, employing an electric pick-up and high frequency modulation is possible without radical changes in the mechanical construction. The difficulties arising out of the necessary use of very short waves are overcome partly by housing the entire "transmitter" or modulator arrangement in the tone arm thus avoiding conductors of substantial length and the introduction of feed back circuits by undesired capacitive or inductive couplings. Although the "receiver" or arrangement connected with the speaker is more complex than the arrangement which has to be used in connection with the usual arrangement, this type of arrangement is merely a copy of the usual receiver which is a standard product and, therefore, does not cause manufacturing or other difficulties. The suppression of noise, however, may be carried to a degree which is unobtainable in ordinary arrangements even of the best quality and it may be further improved by using limitors and the usual arrangement for the suppression of the noise component, as used in connection with frequency or phase modulation.

The arrangement described may be used with phase modulation, the necessary changes being obvious to the experts skilled in the art.

What I claim is:

1. A frequency modulated sound reproduction arrangement with an electric pick up provided with a stylus, an oscillator, including an oscillator circuit and a receiving and reconverting arrangement for frequency modulated oscillations, comprising an inductance coil in the oscillation circuit, a transmission coil arranged concentrically to said inductance coil for transmitting oscillations to the receiving and reconverting arrangement, both coils being arranged with their axis intersecting the axis of the stylus at right angles thereto, a movable metallic core, fixedly attached to the stylus and forming a unitary structure with the same, said core being arranged at right angles to the stylus and arranged to project into the space encircled by the coils.

2. A frequency modulated sound reproduction arrangement with an electric pick up provided with a stylus, an oscillator including an oscillator circuit and a receiving and reconverting arrangement for the frequency modulated oscillations, comprising an inductance coil, connected with said oscillation circuit and arranged at right angles to said stylus, said coil having a hollow interior, a cylindrical metallic plunger projecting into and axially movable within the hollow interior in the interior of the inductance coil, and attached to said stylus at right angles to the same, so as to form a unitary structure with it, damping means for said stylus projecting into the hollow interior of the coil and applied against said plunger and further damping means aligned with the aforesaid damping means and directly applied against the stylus.

3. A frequency modulated sound reproducer,

comprising a movable hollow tone arm, an electric pick up mounted on said tone arm provided with a stylus, an oscillator including an oscillating circuit, mounted within said tone arm, an adjusting condenser and an inductance coil in said circuit, the latter mounted with its axis at right angles to said stylus within said tone arm, a movable core for said inductance coil attached to said stylus, a receiving and reconverting arrangement outside of said tone arm and means to transmit the modulated oscillations produced in said oscillator and oscillator circuit to said receiving and reconverting arrangement including a coil concentric with said inductance coil.

4. A frequency modulated sound reproducer, comprising a movable hollow tone arm, having an end portion inclined with respect to the remainder of the tone arm, frame members within said end portion, an electric pick up provided with a stylus mounted between the said frame members in the end portion of the tone arm, aligned resilient means for carrying said stylus between the frame members in said tone arm, an oscillator including an oscillator circuit, mounted in the hollow interior of the tone arm, an adjustable condenser within said circuit, having adjusting means projecting from said tone arm, an inductance coil with a hollow interior, arranged within said oscillation circuit in the end portion of the tone arm close to the stylus, a movable metallic plunger forming a core for said inductance, attached to said stylus and projecting into the hollow interior of the same, and damping members for said stylus at right angles to the aligned resilient supporting means of the stylus on the frame members, and carried by said frame members, one of said damping members being adjustable with respect to said frame.

5. A sound reproducer for frequency modulated sound reproduction systems operated by the sound track of a phonographic record comprising a tone arm, an electric pickup provided with a stylus, an oscillator, including an oscillating circuit the latter including an inductance coil carried by said tone arm, frame members on said tone arm, means for carrying the stylus, arranged on said frame members, a metallic cylindrical plunger attached to said stylus, projecting substantially at right angles from the same, said plunger and said stylus forming a unitary structure, said inductance coil having a hollow interior and being arranged at right angles to said stylus, said plunger projecting into the interior of the

aforesaid coil and forming a movable core for the same, damping means for said unitary structure arranged in the axis of the plunger including a non-metallic core member inside said coil, arranged coaxially with the plunger and attached to one of the frame members, a resilient cushioning member, carried by said non-metallic core and applied against the end face of the plunger, a further damping member arranged coaxially with the plunger and applied against the stylus and an adjustable supporting member for said damping member carried by a further frame member.

6. A sound reproducer for frequency modulated sound reproduction systems, operated by the sound track of a phonographic record, comprising a tone arm, an electric pickup carried by said tone arm and provided with a needle support, an oscillator including an oscillator circuit, carried by said tone arm said oscillator circuit further including, an inductance coil arranged with its axis intersecting the axis of the needle support and arranged at right angle thereto, frame members associated with said tone arm, holding means for the needle support on said frame members and damping means associated with the same, arranged along a line intersecting the axis of the needle support and at right angles thereto and to the plane passing through the said axis and through the axis of the coil, and further damping means arranged along the last named axis of the coil for damping free axial movements along said axis.
